UNITED STATES PATENT OFFICE.

FREDERICK VAN PATTEN, OF AUBURN, NEW YORK, AND LEANDER PARMELEE, OF NEW HAVEN, CONNECTICUT.

SHOE-LACE FASTENER.

SPECIFICATION forming part of Letters Patent No. 494,766, dated April 4, 1893.

Application filed July 9, 1892. Serial No. 439,526. (No model.)

To all whom it may concern:

Be it known that we, FREDERICK VAN PATTEN, residing at Auburn, in the county of Cayuga and State of New York, and LEANDER PARMELEE, residing at New Haven, in the county of New Haven and State of Connecticut, citizens of the United States, have invented a new and useful Lace-Fastener, of which the following is a specification.

10 This invention relates to certain new and useful improvements in lace-fastenings, and it consists of the construction and arrangement of the parts thereof as will be more fully hereinafter described and claimed.

15 The object of this invention is to simplify the construction and arrangement of the parts of the devices as set forth and render them more efficient as a securing means, and also provide a slight yielding movement of the 20 same to somewhat relieve the rigidity of the upper portion of the lace, and at the same time adapt the same for easy and ready engagement.

In the drawings: Figure 1 is a perspective view of the shoe, showing the improved fastening in connection therewith, and representing one form of application thereof. Fig. 2 is a perspective view of the improved device detached. Fig. 3 is a similar view of the 30 parts of the device disconnected. Fig. 4 is a detailed perspective view of a different form of supporting plate. Fig. 5 is a perspective view of a modified form of button used in connection with the device. Fig. 6 is a perspective view of a still further modification. Fig. 7 is a transverse vertical section on the line $x-x$, Fig. 6.

Similar numerals of reference are employed to indicate corresponding parts in the several 40 views.

Referring to the drawings, the numeral 1 designates the supporting-plate, which is bent upon itself and adapted to be placed over the edge of the upper, as shown in Fig. 1, and 45 either secured by a rivet 2, as shown in Figs. 1, 2, and 3, or may be formed with a downwardly-bent tongue 3, adapted to be passed through an opening 4, and upset against the inner side of the upper, the said tongue 3, and 50 opening 4, being formed on opposite sides

of the plate. A post 5, is secured to the plate 1, in each instance, and adjacent to said post is formed a round, square, or elliptical opening 6, through which extends the shank 7, of a head or button 8. As shown in Fig. 5, the 55 said shank 7 may be of an ordinary looped form, or, as seen in the remaining figures, be in the form of a rigid post having a T-head 9, in connection with the lower portion thereof. When the form of shank shown in Fig. 5 is employed, a piece of wire or other suitable 60 material is passed through the loop as at 10, and bears against the under side of the outer portion of the plate 1, to prevent separation of the shank from the said plate, and the T- 65 head hereinbefore set forth also has a similar function in connection with the said plate in the other forms of the device shown. In each instance the shank of the head or button has movement in the opening of the plate 1, 70 through which it passes, and thereby provides means for readily engaging the lace in connection therewith, and at the same time, when the lace is in engagement with the shank of the head or button, it draws the latter over 75 toward the said post 5, and assists in retaining the lace in connection with the fastening to avoid accidental disengagement thereof. It will be seen from the accompanying drawings 80 that the head or button is of considerable extent and the last-named operation in holding the lace in securement is also attributable and facilitated in a measure by said construction.

As shown in Figs. 6 and 7, the plate 1 has 85 four spurs 11 in connection therewith, and one side thereof struck up to form a post 12. The opening in the center of the plate to receive the shank of the head or button is the same in this instance as in the other forms heretofore set forth, but on each side of said opening are indentations 13, extending from the inner side to the outer side of the said plate in order that the T-head on the shank of the head or button in this form of the device may 95 extend upward into the said indentations and hold the said head or button sufficiently elevated for proper engaging operation. It will be seen that the plate 1, and the post in the device shown by Figs. 6 and 7, are of in- 100

tegral formation and constructed of suitable sheet-metal, thereby making the manufacture thereof simple and comparatively inexpensive.

5 It will be seen that the essential feature of this invention, and as embodied in all the forms shown, is the supporting-plate, movably carrying a head or button with an adjacently situated post, the latter being rigid. 10 When the lace is applied to the fastening, it is preferably arranged as shown in Fig. 1, and crossed between the rigid post and movable head, though from time to time other means of arranging the lace in connection with the 15 fastening may be ascertained and form an equally efficient securement; and after engaging the lace with the fastening, the end of said lace may be inserted between the shoe and the stocking, when the device is applied 20 to a shoe, or be otherwise hidden, as found convenient and desirable. It will be seen that the T-head 9 and loop 10 serve in the capacity of a shoe, and that the head 8, together with its shank, has an oscillating 25 movement in a straight line only relatively to the rigid post 5.

It will be seen that the lace, by being crossed between the post and head, is thereby held against accidental disengagement by 30 forcing the parts against each other and thereby producing a binding.

The device herein set forth is adapted for use wherever a lace may be employed, such as gloves, belts, corsets, boots and shoes, and 35 other articles.

Having thus described the invention, what is claimed as new is—

1. In a lace fastener, the combination of a supporting-plate as set forth having an opening therein and a post thereon, and a head or button having a shank freely movable in the plane of said post and to and from the latter, and a shoe on the inner end of the shank adapted to bear against the underside of the outer portion of said plate and the head or button adapted to clamp a lace crossed between said post and head, substantially as described.

2. In a lace fastening, the combination of a U-shaped supporting-plate having one end reduced and forced through an opening in the opposite end, a rigid post, and a button or head having a shank and movable in the plane of and to and from said post and adapted to clamp a lace crossed between said post and button or head, substantially as described.

3. In a lace fastening, the combination of a plate having a rigid post projecting therefrom, and an oscillating head or button movable in the plane of said post and to and from the latter, and standing outwardly from said plate, substantially as described.

In testimony that we claim the foregoing as our own we have hereto affixed our signatures in the presence of two witnesses.

FREDERICK VAN PATTEN.
LEANDER PARMELEE.
